UNITED STATES PATENT OFFICE.

DAVID LE ROY MANTLE, OF McALESTER, OKLAHOMA.

INVISIBLE PIN.

1,321,534.

Specification of Letters Patent. Patented Nov. 11, 1919.

Application filed June 7, 1919. Serial No. 302,374.

To all whom it may concern:

Be it known that I, DAVID LE ROY MANTLE, a citizen of the United States, residing at McAlester, in the county of Pittsburg and State of Oklahoma, have invented 5 certain new and useful Improvements in Invisible Pins, of which the following is a specification, reference being had to the accompanying drawings.

10 This invention relates to an improved invisible pin, and an object of the invention is to provide a device of this kind, which, when fastened to the bosom of a shirt, the pin is entirely out of sight.

15 A further object of the invention is to provide a pin of this kind including two prongs, one to be secured to a part of the bosom of the shirt that ordinarily carried the buttons, the other prong to engage that 20 portion of the shirt that usually has the buttonholes, the pin being arranged whereby it is invisible.

The invention further aims to provide an invisible pin particularly adapted to all garments, whereby opposite parts of the garment can be easily and quickly fastened by means of the pin, thereby taking the place 25 of buttons, hooks and eyes, etc.

A further object of the invention is to provide 30 an invisible pin particularly adapted as a substitute for buttons, hooks and eyes and the like, so as to be particularly adapted for washable garments.

It is a well known fact that buttons, hooks 35 and eyes and other fasteners on washable garments are lost when the garments are laundered; therefore an object of the present invention is to provide a fastener or invisible pin, which is detachable from the 40 garment when it is sent to the laundry, thereby not only avoiding the loss of the fastener or the pin, but also enabling the garment to be more thoroughly cleaned, and also preventing the garment from being 45 torn, which would be the case with buttons, since the buttons would tend to pull a piece from the garment when caught by moving parts of a washing machine.

A further object of the invention is to 50 provide an invisible pin which can be easily

manipulated with one hand, in order to fasten or unfasten the pin.

A further object of the invention is to provide an invisible pin comprising a pin frame, which may be preferably diamond 55 shaped, but not necessarily, including a pair of prongs spanning the frame at its greatest dimension, in combination with holding means at one end of the frame to retain the pins in their fastened positions.

60 While the design and construction at present illustrated and set forth is deemed preferable, it is obvious that as a result of a reduction of the invention to a more practical form for commercial purposes, the invention 65 may be susceptible to changes, and the right to these changes is claimed, provided they are comprehended within the scope of what is claimed.

The invention comprises further features 70 and combination of parts, as will be hereinafter set forth, shown in the drawings and claimed.

In the drawings:

Figure 1 is a perspective view of the improved invisible pin constructed in accordance with the invention.

Fig. 2 is a longitudinal sectional view on line 2-2 of Fig. 1.

Fig. 3 is a view of a portion of the garment, showing the pin in dotted lines as applied, illustrating the fact that it is invisible when in use.

Fig. 4 is a detail view of a blank which forms the clamp or holder 11.

Fig. 5 is a detail view in side elevation of one end of the pin more clearly showing the details of the clamp or holder.

Fig. 6 is a detail view showing long and short prongs 9, and correspondingly shaped 80 suitable sockets or keepers 10^a of the sheet metal clamp or holder.

Referring to the drawings, 1 designates the invisible pin as a whole, and which is constructed of a single length of spring 95 wire, whereby a diamond-shaped frame 2 is constructed.

The substantially central portion of the body of the wire is bent to form a spring coil 3, the portions of the wire beyond the 100

coil 3 are arranged and shaped to provide the sides 4 of the frame. These sides 4 each consist of the portions 5 and 6, which extend at obtuse angles to each other. 5 Where these portions 5 and 6 merge from each other spring coils 7 are provided, said coils acting to restore the sides of the frame to their normal positions, subsequently to relieving pressure upon the opposite sides 10 of the frame. The portions 6 of both sides converge toward each other and are twisted together once or twice as shown at 8, and the portions of the wire beyond the twist 8 constitute prongs 9, which span the frame 15 between its greatest dimension. When the pin is in use, the prongs 9 engage through the garment, and their sharpened extremities engage keepers 10, which are carried by and form parts of a sheet metal clamp 20 or holder 11, which is carried upon the spring coil 3, to reinforce the same, and to prevent excessive destruction of the sides 25 of the frame. The portions 12 of the holder are engaged by the sides of the frame, in order to limit them in their outward expanding actions. In order to release the extremities of the prongs pressure may be applied on the opposite sides of the frame adjacent the spring coils 7 by means of the 30 thumb and forefinger, causing the opposite ends of the frame at the greatest dimension to move from each other, which will remove the terminals of the prongs from their keepers. The prongs 9 will then spring 35 outwardly, thereby permitting them to be detached from the garment.

In order to make the frame of the pin firm and rigid, it is found necessary to render the twist 8 a fixed joint between the 40 twisted parts. This may be accomplished in many different ways, and it is the aim not to be limited to any one particular manner of rendering the twist firm. However, this twist may be made firm and solid, by 45 welding the parts of the twist, or applying solder, or by shaping the twisted parts so they may interlock, or if desired, sufficient pressure may be applied on the twisted parts, so as to cause them to firmly bind 50 together, thereby insuring rigidity or firmness. It is to be understood that any other method may be employed for rendering the twisted parts rigidly fixed relative to each other, without departing from the scope of 55 the invention.

As shown in Fig. 1, the sockets or keepers 10 are of different lengths, and the prongs 9 are of the same length. By virtue of this construction, it will be seen that one of the 60 prongs may be released, by pressing on the opposite portions of the frame adjacent the coils 7, without withdrawing the sharpened end of the other prong from its socket or

keeper. It is obvious that either one of the sockets or keepers 10 in Fig. 1 may be made 65 longer than the other, in order to accomplish this result.

While Fig. 2 is shown and described as being a section on line 2-2 of Fig. 1, it is to be understood that the keepers or sockets 70 10 in Fig. 2 are designed of the same length, and the prongs 9 correspondingly formed, so that the two prongs may be released or withdrawn from the keepers at the same time. 75

In Fig. 5, the long and short sockets or keepers 10 are more clearly shown, enabling one prong to be disengaged from one of the sockets or keepers without disengaging the other prong. 80

In Fig. 6, the idea of permitting one prong or the other to be disengaged from its socket or keeper, for disengaging the other is accomplished, by constructing the prongs of different lengths, and correspondingly forming the sockets or keepers, designated by the numeral 10^a. In this construction, it is obvious that by applying pressure on the opposite sides of the frame, one or the other of the prongs 9 may be 90 disengaged from its keeper, without disengaging the other prong. By constructing the prongs, so that one or the other may disengage from its keeper, without withdrawing the sharpened point of the other 95 prong, permits the retained prong to remain fastened to the garment. However, a greater pressure on the opposite sides of the frame near the coils 7, would also release the longer prong, as well as the shorter 100 prong. It is the aim that the sides of the frame, that are in parallelism with each other, are designed to be arranged in the same plane in edge view as seen in Fig. 2.

The invention having been set forth, 105 what is claimed as new and useful is:

1. In an invisible pin, a frame comprising opposite sides having portions extending at obtuse angles, said sides, from where the portions extend at such angles having 110 spring coils, a pair of prongs carried by one end of the frame, normally urging laterally in opposite directions, the other end of the frame having spring means and provided with keepers, adapted for the reception of the terminals of the prongs, whereby, when pressure is applied on the opposite sides of the frame in a plane at right angles to the laterally urging action of the prongs, the terminals of the prongs 120 may be withdrawn from the keepers. 115

2. An invisible pin constructed from a single length of spring wire, the central portion of the body of which being turned to form a spring coil, holding means for the 125 coil, the portions of the body of the wire

beyond the spring coil being bent to form
5 spring sides having portions at obtuse
angles to each other, at the point where said
obtuse angularly extending portions connect
having spring coils, the sides beyond the
second spring coils at a point remote from
the first spring coil being twisted together,
and parts of the wire beyond the twist
terminating in prongs having sharpened
10 terminals, said holding means having

keepers for the reception of the sharpened
terminals.

In testimony whereof I hereunto affix
my signature in the presence of two wit-
nesses.

DAVID LE ROY MANTLE.
